United States Patent

Des. 240,616
Patented July 20, 1976

240,616

TIRE

Chester J. Gasowski, North Canton, and Dennis B. Granger, Norton, Ohio, John A. Hutz, Orlando, Fla., and Terrence M. Ruip, Akron, Ohio, assignors to The Goodyear Tire & Rubber Company

Filed Jan. 23, 1975, Ser. No. 543,398

Term of patent 14 years

Int. Cl. D12—15

U.S. Cl. D12—146

The figure is a perspective view of a tire showing our new design, it being understood that the tread design is repeated throughout the circumference of the tire, as shown schematically by solid lines, the opposite side being substantially the same as that shown.

We claim:

The ornamental design for a tire, substantially as shown and described.
